CLAIM

The ornamental design for a circular saw guard, as shown and described.

DESCRIPTION

FIG. 1 is a perspective view of a circular saw guard (the broken lines showing a circular saw housing are for illustrative purposes only and forms no part of the claim);

FIG. 2 is a front view thereof (the broken lines showing mounting portions extending from the left side thereof are for illustrative purposes only and forms no part of the claim);

FIG. 3 is a rear view thereof (the broken lines showing mounting portions extending from the left side thereof are for illustrative purposes only and forms no part of the claim);

FIG. 4 is a top view thereof (the broken lines showing mounting portions extending from the left side thereof are for illustrative purposes only and forms no part of the claim);

FIG. 5 is a bottom view thereof (the broken lines showing mounting portions extending from the left side thereof are for illustrative purposes only and forms no part of the claim);

FIG. 6 is a right side view thereof; and,

FIG. 7 is a left side view thereof (the broken lines showing mounting portions extending from the left side thereof are for illustrative purposes only and forms no part of the claim).
